UNITED STATES PATENT OFFICE.

GEORGE B. MAEGLY, OF KANSAS CITY, MISSOURI.

PAPER-FEED MECHANISM.

No. 902,751.

Specification of Letters Patent.

Patented Nov. 3, 1908.

Application filed February 24, 1908. Serial No. 417,330.

To all whom it may concern:

Be it known that I, GEORGE B. MAEGLY, a citizen of the United States, residing at Kansas City, in the county of Jackson and State of Missouri, have invented certain new and useful Improvements in Paper-Feed Mechanism, of which the following is a specification.

This invention relates to paper feed mechanism, and more especially to mechanism for successively removing sheets of paper from a stack and advancing them one by one to the point desired, my object being to produce a mechanism of this character which operates efficiently and reliably and which is of simple, strong, durable, compact and inexpensive construction.

To this end the invention consists of certain novel and peculiar features of construction and organization as hereinafter described and claimed; and in order that it may be fully understood, reference is to be had to the accompanying drawing in which—

Figure 1, is a vertical section taken on the line I—I of Fig. 2. Fig. 2, is a top plan view of the same. Fig. 3 is a vertical section on the line III—III of Fig. 2, but with the friction roller occupying its inoperative position.

In the said drawing, 1 indicates a suitable paper receptacle containing a stack of sheets 2, pressed upward by a follower 3, the follower in practice exerting a yielding pressure by preference though not so shown, as it is of common and well known construction in paper feeding mechanisms.

Superposed upon the sides of this receptacle is a stationary frame consisting of two similar sides 4 and bridging the rear end of the receptacle and extending transversely thereof and journaled in the stationary frame is an idler roller 5, for the purpose of preventing the complete upward ejection of the sheets of paper from the rear end of the receptacle, a roller being employed for this purpose to eliminate friction in the advance movement of each sheet.

6 indicates a thin bed-plate for frame 4, overlapping the front end of the stack of paper to limit the upward movement of the same at such end. 7 is an arch frame rising from the sides 4 of the stationary frame at the rear end of the bed-plate, and rearward of said bed-plate and between the sides or legs of the said frame, the latter is provided

with depending arms 7^a having vertical slots 8 wherein fit slidingly the boxes 9 in which is journaled a transverse shaft 10 incapable of endwise movement because of the sleeve 60 10^a secured upon it snugly between said arms 7^a. Secured upon the ends of shaft 10 is a roller consisting by preference of two similar sections 11 each equipped peripherally with a tread or friction surface 12 of 65 rubber or equivalent material, springs 13 occupying slots 8 and interposed between the boxes 9 and the underlying ends of the slots 8, normally holding the roller yieldingly elevated above the plane of the stack of 70 paper as shown in Fig. 3.

Forward of and above shaft 10, and journaled in the sides or legs of arch-frame 7, is a shaft 14, adapted to be continuously driven by a belt, or its equivalent, not shown, 75 engaging pulley 15, secured to one end of said shaft, and secured upon said shaft between the standards 7 is a cam, which, like the roller, preferably consists of two sections 16, provided with concentric rubber or 80 equivalent tired portions 17, the cam sections being adapted once in each revolution to engage and depress and incidentally turn the roller sections, the depression-action continuing until the latter engage the topmost 85 sheet of the stack of paper, when the concentric portions of the cam sections more positively effect rotation of said roller sections in the direction indicated by the contiguous arrow Fig. 1, for the purpose of 90 drawing the front portion of the topmost sheet of paper rearward from under the overlapping end of the bed-plate, the sheet between the friction roller 11, and roller 5, buckling or bowing upward substantially as 95 shown in dotted lines, Fig. 1.

Secured rigidly on the shaft 14, are one or more rubber-tired segments preferably one at the outer side of each section, and each segment by preference consists of two 100 sections fitting adjustably together for the purpose of varying the length of the segment. As shown, each segment consists of a section 18, and a section 19, the former being equipped with a clamping bolt 20 extending 105 through a slot 21 in section 19, the said slot being preferably enlarged at its inner side at 22 to receive the head of the bolt and the washer 23 mounted on the bolt. The segments are preferably arranged upon the 110 shaft with their front ends occupying a radial plane rearward of one of the rear ends

of the cams. By this arrangement it will be apparent that immediately after the cams pass out of engagement with the roller sections 11, the latter are forced upwardly by 5 their springs 13 and release the buckled sheet, permitting the same under its gravitational and resilient tendency to straighten out, and in such straightening action, overlap at its front end, the rear end of bed-plate 6. Immediately after this action occurs, 10 the front end of the segments come into engagement with said overlapping front end of the sheet as shown in Fig. 3, and force said sheet forward upon the bed-plate 15 a distance equal to the length of the segment, after which, its advance may be continued by any suitable mechanism. As shown, the length of the segment peripherally measured, is less than that of the sheet. 20 In practice it would have to be about equal to the length of the sheet, or the advance of the latter would have to be continued by other means in order to draw it out of the way of the following sheet, as will be readily understood.

From the above description it will be apparent that I have produced a paper feed mechanism possessing the features of advantage enumerated as desirable and I wish 30 it to be understood that I do not desire to be restricted to the exact details of construction shown and described, as obvious modifications will suggest themselves to one skilled in the art.

Having thus described the invention, what I claim as new and desire to secure by Letters-Patent, is:—

1. A paper feed mechanism, comprising a receptacle for a stack of sheets of paper, a bed-plate overlapping the front end of said stack, a feed roller near the rear end of the bed-plate, and a driven shaft provided with a cam to engage and force said roller against the paper and a tread surface to impart rotation to said roller to cause the same to withdraw the front end of the engaged sheet from below the overlapping end of the bed-plate.

2. A paper feed mechanism, comprising a receptacle for a stack of sheets of paper, a bed-plate overlapping the front end of said stack, a feed roller near the rear end of the bed-plate, a driven shaft provided with a cam to engage and force said roller against the paper, and a tread portion to impart rotation to said roller to cause the same to withdraw the front end of the engaged sheet from below the overlapping end of the bed-plate, and means to withdraw said feed roller from engagement with the paper as its 55 rotative action ends.

3. A paper feed mechanism, comprising a receptacle for a stack of sheets of paper, a bed-plate overlapping the front end of said 60 stack, a feed roller near the rear end of the

bed-plate, a driven shaft provided with a cam to engage and force said roller against the paper and a tread portion to impart rotation to said roller to cause the same to withdraw the front end of the engaged sheet from below the overlapping end of the bed-plate, means holding the rear end of the stack of paper substantially immovable to cause the sheet engaged by said roller to buckle upward, and means to withdraw said roller from engagement with the paper as its rotative action ends to permit the buckled sheet to overlap at its front end, the rear end of the bed-plate.

4. A paper feed mechanism, comprising a receptacle for a stack of sheets of paper, a bed-plate overlapping the front end of said stack, a feed roller near the rear end of the bed-plate, a driven shaft provided with a cam to engage and force said roller against the paper and a tread portion to impart rotation to said roller to cause the same to withdraw the front end of the engaged sheet from below the overlapping end of the bed-plate, means holding the rear end of the stack of paper substantially immovable to cause the sheet engaged by said roller to buckle upward, means to withdraw said roller from engagement with the paper as its rotative action ends to permit the buckled sheet to overlap at its front end, the rear end of the bed-plate, and means to engage the sheet overlapping the bed-plate, and move it forwardly upon the latter.

5. A paper feed mechanism, comprising a receptacle for a stack of sheets of paper, a bed-plate overlapping the front end of the stack, a feed roller near the rear end of the bed-plate, a driven shaft provided with a cam to engage and force said roller against the paper and provided with a tread portion to impart rotation to said roller to cause the same to withdraw the front end of the engaged sheet from below the overlapping end of the bed-plate, means holding the rear end of the stack of paper substantially immovable to cause the sheet engaged by said roller to buckle upward, means to withdraw said roller from engagement with the paper as its rotative action ends to permit the buckled sheet to overlap at its front end, the rear end of the bed-plate, and a rotating segment to engage the sheet overlapping the bed-plate and feed said sheet forwardly upon the latter.

6. A paper feed mechanism, comprising a receptacle for a stack of sheets of paper, a bed-plate overlapping the front end of the stack, a feed roller near the rear end of the bed-plate, a driven shaft provided with a cam to engage and force said roller against the paper and provided with a tread portion to impart rotation to said roller to cause the same to withdraw the front end of the engaged sheet from below the over-

lapping end of the bed-plate, means holding the rear end of the stack of paper substantially immovable to cause the sheet engaged by said roller to buckle upward, means to withdraw said roller from engagement with the paper as its rotative action ends to permit the buckled sheet to overlap at its front end the rear end of the bed-plate, and a rotating extensible segment to engage the sheet overlapping the bed-plate and feed said sheet forwardly upon the latter.

7. The combination with a receptacle open at its upper end and containing a stack of paper, a bed-plate overlapping the front end of the stack, a follower to press the stack of paper up against said roller and bed-plate, a feed roller near the rear end of the bed-plate, a driven shaft provided with a cam to engage and force said feed roller against the paper and provided with a tread

portion to impart rotation to said feed roller to cause the same to withdraw the front end of the engaged sheet from below the overlapping end of the bed-plate, means holding the rear end of the stack of paper substantially immovable to cause the sheet engaged by said feed roller to buckle upward, means to withdraw the feed roller from engagement with the paper as its rotative action ends to permit the buckled sheet to overlap at its front end the rear end of the bed-plate, and means to engage the sheet overlapping the bed-plate and move it forwardly upon the latter.

In testimony whereof I affix my signature, 35
in the presence of two witnesses.
